CLAIM

We claim the ornamental design for a compressor, as shown and described.

DESCRIPTION

FIG. 1 is a right side perspective view of the compressor; FIG. 2 is a left side view of the compressor shown in FIG. 1;

FIG. 3 is a top view of the compressor shown in FIG. 1; FIG. 4 is a right side view of the compressor shown in FIG. 1;

FIG. 5 is a rear view of the compressor shown in FIG. 1; FIG. 6 is a bottom view of the compressor shown in FIG. 1; and,

FIG. 7 is a front view of the compressor shown in FIG. 1. The broken lines are included for the purpose of illustrating portions of the compressor that form no part of the claimed design.
